CYLINDER FEEDING DEVICE FOR PROGRESSIVE WASHING MACHINES

Milton L. Neher, Coral Gables, Fla.

Application November 6, 1947, Serial No. 784,421

8 Claims. (Cl. 68—10)

1

This invention relates to a continuous washer of the commercial type and is more specifically directed to an improved construction and combination of washing cylinders and rotors and the driving means for said cylinders.

In machines of this kind it always has been a problem to move and drive the clothes washing cylinders from rotor to rotor in multi-rotor washers and wherein the rotors do normally operate at different rotational velocities. The introduction of an extraction cycle brings in a rotor of high speed velocity and unidirectional in contrast to adjacent rotors which operate at relatively low speeds and may or may not be unidirectional in operation.

It has also been the practice in the past to lock the cylinders to the rotors in their various washing, rinsing, extracting, drying or fluffing stations. This required the alignment of rotors into certain predetermined angular relationships to facilitate further locking of the cylinders to the rotors after each advancement from stage to stage is performed.

The more modern practice in horizontal washers of these continuous types has been to eliminate alignment requirements and to carry out the entire washing cycle without stopping the rotors or cylinders in their progress through the machine by virtue of the concentrically symmetrical designs of the cylinders and by other improvements that directly contribute to the operational phases of these kinds of washers.

Various means have been employed to pass and guide the cylinders along the lane of rotors and across the gaps between such rotors, and more specifically to releasably connect or join the cylinders to the rotors containing the same after each shift of the rotors. This problem presented the most difficulty during the displacements of the cylinders from slow speed to high speed stages, and vice versa, it being understood that periodic opposite oscillation or rotation of adjacent rotors complicates this transfer problem.

Various frictional means for cooperation between the rotors and the cylinders nested therein have been used such as tracks or ways made of rubber, wood or other fairly wear resisting materials of frictional characteristics. But these tracks or ways wear through continued use, and also, continual subjection to water, soaps, water softeners, and washing chemicals also affects the life and efficiency of the tracks and ways causing undesirable maintenance costs and equally costly shut downs of the washing units.

It is the main object of the present invention to simplify the continuous washer rotor and cylin-

2

der construction in such a manner as to provide effective cylinder revolving means adapted for long life and efficient operation under all normal conditions of operation in commercial types of washers of this kind.

It is another object of the invention to introduce an arrangement for driving the cylinders within the rotors which has the ability to tone down or step up the rotational velocity of the cylinders as they pass between the rotors from stage to stage wherein such adjacent rotors are operating at widely different velocities or in opposite directions at the time the cylinders are being transferred.

Other objects including the reduction in maintenance and simplicity of design for low first cost and low operating cost, etc., shall all appear in the following detailed description having reference to the accompanying drawings illustrating a preferred arrangement and combination of elements for carrying out the inherent contributions of the present invention and forming a part of this specification.

In the drawings:

Fig. 1 is a general diagrammatic layout of a continuous commercial washing machine embodying the newly designed cylinder rotor combination which is adapted for advancing the cylinders through the machine from stage to stage and also performing the dual function of driving each cylinder or group of cylinders in the various stations of operation in the washer;

Fig. 2 is a transverse vertical cross sectional view taken through the machine along the line 2—2 in Fig. 1 to diagrammatically illustrate certain other details of construction and the general arrangement of the various mechanisms;

Fig. 3 is a side elevational view of one of the improved cylinders utilized in the washer and as it appears when bodily removed from the rotors;

Fig. 4 is a transverse cross sectional view through one peripheral wall of the cylinder and substantially as seen along the line 4—4 in Fig. 3; and

Fig. 5 is a plan view of a modified washer construction illustrating another arrangement wherein the cylinders pass through dead zones comprising free wheeling rotors having no driving connection, this representing a means for transposing a cylinder under relative velocity conditions between adjacent rotor sections.

The general layout of the continuous washer installation may best be understood by reference to Fig. 1 in the drawings and consists of the washer 1 divided into compartments 2, 3, 4 and 5,

together with loading and unloading stations 6 and 7 to be serviced by means of a continuous overhead track 8 leading from a cylinder loading platform 9 to the washer and away from the latter to a cylinder unloading platform 10.

The compartments 2, 3, 4 and 5 may or may not be divided into smaller divisions to provide different washing and rinsing stages for the cylinders but for the purposes of this invention and for the sake of clarity such extra details have been omitted. Fig. 1 illustrates a plurality of rotors 11, 12, 13, and 14 disposed in axial alignment and in the compartments 2, 3, 4 and 5 respectively.

The individual washing cylinders are shown at 15—15 throughout the washer 1 and in the rotors 11 to 14, the entire group of cylinders being arranged for endwise progress through the machine as may be brought about through suitable means such as a hydraulic ram 16 that is controlled by a hydraulic power cylinder 17.

All of the rotors are supported for rotation upon suitably mounted guide rollers 18 and 19 as seen in Fig. 2 with each rotor having a plurality of oppositely disposed buckets 20 and 21 arranged about their periphery to scoop up the water from the baths provided in each compartment where needed. The liquid level is usually maintained below the cylinders as at 22 in Fig. 2 so that the solutions may be independently segregated while endwise movement of the cylinders 15 from compartment to compartment can be accomplished freely.

The rotors 11, 12, 13 and 14 are driven by means of belts 23, 24, 25 and 26 connected with pulleys such as 27 and 28 secured to drive shafts 29 and 30, the various drives being independent and arranged for different speeds to carry out the washing cycle. As seen in Fig. 1, rotors 11 and 12 may be revolved at 40 R. P. M. first in the one direction for a set time and then in the other direction, either together or on off-time intervals. Rotor 13 constitutes the extraction cycle and is usually driven at relatively high speeds in one direction at a rate of approximately 600 R. P. M. Then the fluffing and drying rotor 14 is again rotated at slower speeds either unidirectionally or reversibly.

In carrying out the advance of the cylinders 15 through the machine from stage to stage, the cylinders 15 have been designed to easily make the transposition from one rotor to the next rotor without changing or interfering with the rotor actuation and without reducing the relative speeds of the rotors or bringing the same to a stop at changeover intervals. In addition, the cylinders 15 have further been designed to coat frictionally with the rotors for the purpose of driving the cylinders at rotor speeds, overrunning speeds in reversible rotor operation, and to conveniently and efficiently make the transition between rotors.

Figs. 3 and 4 show the main features associated with the cylinders 15 which contribute to carry out the objects of this new arrangement and coaction between rotors and cylinders. Each cylinder 15 is of the usual cylindrical sheet metal construction having a perforated body 31 with a loading door end 32 and a dead end 33, the door end carrying a friction pad 34, while the dead end carries an antifriction button 35. The cylinders are advanced through the contacting members 34 and 35 under the action of the ram 16, and since the members 34 and 35 make adjacent cylinders rotationally independent, 75

changes in the speed or direction of rotation of the individual cylinders through rotors or from rotor to rotor will not be affected.

Each of the cylinders 15 is provided with at least two frictional driving bands 36 and 37 annularly secured to the cylinder body 31 and at the leading and trailing ends of the cylinder comprising the dead end 33 and door end 32 of the cylinder. The interiors of the rotors are smooth but their diameters are all alike and only slightly larger than the outside diameters of the bands secured to the cylinders. The clearance between the rotors and bands is such as to permit lateral or endwise displacement of the individual cylinders and yet to provide sufficient normal frictional contact due to the weight of the cylinders and clothes, this action also being aided by any off-center loads in the cylinders which loads further act to increase the necessary frictional driving union between cylinders and rotors.

Interchangeability of the bands or replacement thereof may be accomplished by securing the bands 36 and 37 to the bodies 31 of the cylinders 15 by screws 38 or through other attachment devices. Furthermore, the bands may be varied in width to suit conditions of operation and to properly span the gaps between rotors as the cylinders are actuated lengthwise through the washer.

With cylinders of this construction, the same may be advanced through the washer, and from rotor to rotor with each cylinder automatically converting its rotational speeds from one rotor to the next rotor through the frictional driving bands. Also, since the bands are spaced, each band will have a different reaction when the cylinder starts to span the gap between rotors, and the bands will have independent reactions to transmit to the cylinder to neutralize the cylinder speed during the transition between adjacent rotors travelling at different rates of rotation or in opposite directions.

It must also be understood that each band must support its share of the cylinder load and that as the cylinder moves across the gap between adjacent rotors, the load distribution is also transposed from the first rotor toward the second rotor so that the second rotor gradually dominates as to the frictional driving action introduced to rotate the cylinder during this transition. This change from rotor to rotor may be influenced by using band materials of different coefficients of friction, but as shown in the drawings, both bands 36 and 37 are made of the same material.

Thus, with the use of smooth interior rotors, throughout the washer and by banding the cylinders in the manner described, smooth and efficient cyclic operation is possible in a continuous commercial washer with little if any interruptions by reason of the mechanism utilized for running the individual cylinders.

One modification contemplated in the construction disclosed and described will be to use a pair of dead or free wheeling rotors between adjacently disposed and variably driven rotors as shown in Fig. 5. This view diagrammatically illustrates rotors 40, 41, and 42 which are driven at different speeds or reversibly by operation through belts 43, 44 and 45. A pair of dead or free wheeling rotors 46 and 47 are mounted for free and independent rotation upon rollers 48—48 and 49—49, and operate in direct alignment with adjacently located driven rotors. Rotors 46

and 47 each have at least one cylinder capacity and thus may be considered as snubbing the rotational speeds of cylinders in their progress through the washer or as activating the cylinder rotations, all as primarily determined by the speed and direction of rotation of the adjacent driven rotors. Since the cylinders also are free wheeling under frictional restraint in each rotor, a dual action transition is accomplished in the Fig. 5 washer by the introduction of free wheeling rotors.

Other changes and modifications are also contemplated in the form of the invention shown and described as well as in the details of the parts and the general design. All such possible variations and modifications shall, however, be governed by the breadth and scope of the following claims appended hereto.

What I claim is:

1. A multiple cylinder washer arranged for continuous operation and having means to supply washing fluid to the cylinders therein comprising at least two independently operable rotors disposed in axial alignment, clothes holding cylinders arranged for guided passage through each of said rotors and therebetween, actuating mechanism to move said cylinders through said rotors, drive means to independently revolve each of said rotors, and means to transmit the motion of said rotors to said cylinders comprising at least one band on each cylinder disposed for frictional contact with an adjacent interior surface of said cylinder guiding rotors.

2. A multiple cylinder washer arranged for continuous operation and having means to supply washing fluid to the cylinders therein comprising at least two independent rotors positioned in separated axial alignment, clothes holding cylinders arranged for endwise passage through the respective rotors and therebetween, actuating mechanism to move said cylinders endwise through said rotors, drive means to independently revolve each of said rotors, and cylinder drive means for frictionally transmitting the motion of said rotors to the cylinders comprising at least two bands carried by each cylinder in spaced relation to each other and axially of said cylinder, said bands each being of a width to bridge the space between the axially separated rotors as said actuating mechanism moves said cylinders through and between said rotors.

3. In a progressive cylinder washing machine having washing fluid supply means for said cylinders, a tubular rotor supported for turning about its axis, a clothes holding cylinder having an external diameter to substantially fit the interior diameter of said tubular rotor, drive means connected to revolve said tubular rotor, and friction mechanism to transmit the rotary motion of said rotor to said cylinder comprising at least one peripheral band on said cylinder having an outer diameter approximately equal to the internal diameter of said rotor to frictionally contact said rotor, said cylinder and rotor being relatively movable peripherally and axially.

4. A washing machine comprising a housing, washing fluid supply means for said housing, clothes washing mechanism disposed within said housing and comprising a series of independently operable rotors arranged in axial alignment and each having their axial outer ends open, operative means connected for independently rotating said rotors, clothes holding containers movably positioned adjacent each other within said rotors and along the common axes thereof, and actu-

ating means arranged for engagement with at least one of said containers to move all containers axially through said rotors and therebetween through adjacent open ends thereof, and drive transmitting means to rotate said containers in said rotors respectively comprising bands surrounding each of said containers and adapted for frictional engagement within the interior surfaces of said rotors to frictionally transmit the rotative motion of the rotors to said containers, and means to convey said washing fluid to said containers.

5. A washing machine comprising a housing, washing fluid supply means for said housing, clothes washing mechanism disposed within said housing and comprising a series of individually operable rotors arranged in axial alignment and each having their axial outer ends open, said rotors being spaced apart axially with gaps between the adjacent ends thereof, operative means connected with said rotors to independently drive such rotors, clothes holding containers movably positioned adjacent each other within said rotors and along the common axes thereof, and intermittently operable actuating means arranged to engage at least one of said containers and to move all the containers axially through said rotors and therebetween through adjacent open ends thereof, and drive transmitting means to rotate said containers in said rotors respectively comprising bands surrounding each of said containers and adapted for frictional engagement within the interior surfaces of said rotors to frictionally transmit the rotative motion of the rotors to said containers, said bands each being of a width that is greater than the width of the open gaps between the adjacent rotor ends, and means to convey said washing fluid to said containers.

6. A washing machine comprising an enclosure, washing fluid supply means for said enclosure, and a clothes washing mechanism disposed within said enclosure and comprising a plurality of individually operable cylindrical rotors rotating upon a common axis and having their axial terminal ends open, operative means connected for independently revolving said rotors, clothes holding cylinders movably positioned adjacent each other within said rotors and along the common axes thereof, and actuating means arranged to contact at least one of said cylinders to move all cylinders axially through the rotors and therebetween through adjacent ends thereof, and drive transmitting means to rotate said cylinders in said rotors respectively comprising spaced bands carried by each of said cylinders and arranged for frictional engagement with the internal surfaces of said rotors to frictionally transmit the rotative motion of the rotors to said cylinders, and coating anti-friction means carried upon the adjacent axially arranged ends of the cylinders to reduce frictional contact between said cylinders comprising a pad on one cylinder and a button on the next adjacent cylinder for anti-frictional contact with said pad, and means to convey said washing fluid to said cylinders.

7. A washing machine comprising an enclosure, washing fluid supply means for said enclosure, and a clothes washing mechanism disposed within said enclosure and comprising a plurality of individually operable cylindrical rotors rotating upon a common axis and having their axial terminal ends open, operative means connected for independently revolving said rotors, clothes holding cylinders movably positioned adjacent

each other within said rotors and along the common axes thereof, operable cylinder drive means connected with each cylinder and arranged for frictional surface contact with the interior surfaces of said rotors respectively, and cooperative actuating mechanisms for bodily moving said cylinders through said rotors and therebetween comprising an actuating unit to contact at least one of said cylinders to move all cylinders in said rotors, and coactive abutment members carried upon the adjacent wall portions of the cylinders comprising a pad on one cylinder and an anti-friction button upon the adjacent cylinder for contact with said pad of said one cylinder and means to convey said washing fluid to said cylinders.

8. A washing machine comprising an enclosure, washing fluid supply means for said enclosure, and a clothes washing mechanism disposed within said enclosure and comprising a plurality 20 of individually operable cylindrical rotors rotating upon a common axis and having their axial terminal ends open, operative means connected for independently revolving said rotors, clothes holding cylinders movably positioned adjacent 25

5
